UNITED STATES PATENT OFFICE.

WILLIAM F. KOBLE, OF CUSHING, OKLAHOMA.

DOUBLE-ACTION OAR.

1,120,944.

Specification of Letters Patent.

Patented Dec. 15, 1914.

Application filed April 4, 1914. Serial No. 829,597.

To all whom it may concern:

Be it known that I, WILLIAM F. KOBLE, a citizen of the United States, residing at Cushing, in the county of Payne and State of Oklahoma, have invented certain new and useful Improvements in Double-Action Oars, of which the following is a specification, reference being had therein to the accompanying drawing.

This invention relates to boat oars and has for its principal object the production of an efficient means to allow an oar to be operated upon a boat, skiff or the like, in such manner as to allow the operator to face the bow of the boat.

Another object of this invention is the production of a simple and efficient means for mounting the oar upon the boat so as to allow the operator to assist in operating the oar by means of a foot treadle attachment.

A still further object of this invention is the production of an efficient means for limiting the swing of the oar-carrying casing upon the supporting bracket.

With these and other objects in view, this invention consists of certain novel constructions, combinations and arrangements of parts as will be hereinafter fully described and claimed.

In the drawings:—Figure 1 is a perspective view of the device applied to a portion of a boat. Fig. 2 is a central, horizontal section through the device. Fig. 3 is a section taken on line 3—3 of Fig. 2. Fig. 4 is a section taken on line 4—4 of Fig. 3. Fig. 5 is a detail perspective of the bracket adapted to limit the swing of the oar-carrying frame upon the support thereof. Fig. 6 is a perspective view of the means for connecting the loop with the handle of the oar mechanism.

By referring to the drawing, it will be seen that 1 designates the boat or skiff upon which the device is adapted to be mounted and upon the side rail of the boat is mounted a substantially U-shaped bracket for supporting frame 2, having laterally-extending feet 3. An oar-carrying frame, comprising a bottom plate 4, is pivotally mounted between the vertically-extending arms 5 of the bracket or frame 2 by means of passing a journal-pin 6 through the depending ears 7 of the plate 4. A cover-plate 8 is carried by the base-plate 4, and this cover-plate is provided with a pair of side flanges 9, which

flanges are secured along their lower edges to the base-plate 4 by means of screws, or other suitable fastening means 10. The ends of the side flanges 9 are cut-away, as indicated at 11, so as to allow the paddle and handle of the oar to have a free lateral swinging movement over the oar-supporting casing or frame.

A primary gear 12 is journaled between the upper and lower plates 8 and 4 of the oar-carrying frame upon a journal pin 13, and this gear 12 carries an operating-handle 14, which operating-handle 14 projects beyond the inner end of the oar-carrying frame, as is clearly illustrated in Figs. 1, 2 and 3. An auxiliary gear 15 is also journaled between the upper and lower plates 8 and 4, and this gear 15 meshes with the gear 12, as is clearly illustrated in Fig. 2. The gear 15 carries upon its outer end a paddle 16, which is adapted to dip in the water over the side of the boat, in the usual manner.

A stop band 17, comprising a substantially U-shaped body, is carried by the upper ends of the upwardly-extending arms 5 of the frame or bracket 2, and the downwardly-extending arms 18 of the stop band 17 are pivotally-secured to the arms 5 by means of pivot-screws 19. A journal block 20 is secured in one corner of the stop band 17 and is provided with a rounded end-piece 21 so as to slide freely over the upper rounded end 22 of one of the vertically-extending arms 5. An adjustable clamping block 23 is carried at the opposite end of the stop band 17 and this clamping block 23 is carried by an adjusting screw 24. The block 23, like the block 20, is provided with a rounded end-face, which is adapted to engage the rounded upper face of the adjacent arm 5, and by turning the screw 24 downwardly upon the stop band 17, it will be seen that this stop band may be held in an adjusted position by swinging the same to the position shown by dotted lines in Fig. 3, for decreasing the amount of vertical swing desired, relative to the oar-carrying casing.

The frame or bracket 2 is provided upon one side thereof with a depending arm 25, which arm is adapted to be fixedly secured to the inner face of one of the side-rails of the boat 1. This bracket 25 is provided with an extending arm 26 upon which arm is journaled a foot-treadle 27. This foot

treadle 27 is provided with a downwardly-extending arm 28 having a foot-engaging member 29 extending laterally therefrom.

5 A connecting hook 30 is secured to the upper end of the foot-treadle 27, as illustrated in Figs. 1 and 3, and this connecting hook 30 is provided with a downwardly-turned end 31, which downwardly-turned end 31 fits over the grooved-portion 32 of

10 the handle 14 of the oar.

It should be understood that the band 17 may be normally held in the position shown in Fig. 1, but if it should be desired to decrease the distance at which the paddle 16 15 may dip into the water, the band 17 may be swung to the position shown in Fig. 3, in dotted lines. As the handle 14 is drawn rearwardly the paddle 16 will also be drawn rearwardly and in this manner the operator 20 of the oar may face the bow of the boat and be enabled to efficiently steer the same. It should be understood that the oar-carrying casing may be readily tilted upon the journal pins 6, but this casing is not journaled 25 so as to allow the same to have any lateral swinging movement, as all of the lateral swinging movement will be supplied through the medium of the coöperation of the handle 14 and the paddle 16.

30 In order to assist in operating the paddle 16 a foot-treadle 27 has been employed, the structure of which has been previously described. By operating the foot-treadle 27 it will be seen that the loop-portion 31 will engage the handle 14 of the oar and assist in oscillating the same, by the oscillation of the foot-treadle 27.

It should be further borne in mind that, owing to the fact a foot-treadle has been 40 attached to the handle, the operator may apply a greater amount of strength to operate the oar, owing to the fact that he may not only apply his manual strength thereto, but he may also apply his entire weight, by 45 forcing his weight directly upon the foot-treadle, and at the same time pulling upon the handle 14.

It should be further understood that by 50 means of the foot-treadle 29 the oar will be greatly assisted in returning the same to its original position, ready for the next stroke.

The gear 12 is provided with a socket portion 32 for receiving the operating handle 14, as illustrated in Figs. 1 and 3. The gear 55 15 is provided with a socket portion 15' for receiving the blade 16 of the oar.

By carefully considering Fig. 6 it will be

seen that the loop 30 is provided with a laterally-extending pin 30', which pin works in a transversely-extending slot 31' carried 61 by the treadle 27. It will be seen that the pin 30' may have a slight lateral swing in the slot 31' to allow for the swing of the handle 14 while operating the paddle 16.

What is claimed is:

1. A device of the class described, comprising a support, a casing carried thereby, a foot-treadle, said foot-treadle provided with a connecting link having a looped upper end, an operating handle, said loop 70 extending around said operating handle and said foot treadle adapted to facilitate the operation of said operating handle.

2. A device of the class described comprising a support, a casing carried thereby, 75 an oar operating mechanism placed within said casing, a stop band extending over said casing, and means for holding said stop band in a set position for limiting the vertical swing of said casing upon said support.

3. A device of the class described comprising a support, said support comprising a plurality of upwardly extending arms, a casing pivotally mounted between said 85 arms, an oar actuating mechanism placed within said casing, a stop band pivotally secured to the upper ends of said arms, and an adjusting screw carried by one end of said band and engaging one of said arms 90 for holding said stop band in a set position for limiting the upward swing of said casing upon said arms.

4. A device of the class described comprising a support, said support comprising 95 a plurality of upwardly extending arms, a casing pivotally mounted between said arms, an oar actuating mechanism carried by said casing, a stop band provided with annularly bent ends pivotally secured to 100 the upper ends of said arms, a thumb screw passing through one end of said band, a clamping block carried by the lower end of said thumb screw, and said clamping block adapted to engage the upper end of one of 105 said arms for firmly holding said stop band in a set position for limiting the upward swing of said casing upon said arms.

In testimony whereof I hereunto affix my signature in presence of two witnesses.

WILLIAM F. KOBLE.
